CLAIM

The ornamental design for a display screen or portion thereof with icon, as shown and described.

DESCRIPTION

FIG. 1 is a front view of a display screen or portion thereof with icon, showing our new design; and,

FIG. 2 is a front view of a display screen or portion thereof with icon showing an alternative embodiment of our new design.

The dot-dash broken lines illustrating portions of the display screen or portion thereof with icon are for illustrative purpose only and form no part of the claimed design.

1 Claim, 2 Drawing Sheets
